UNITED STATES PATENT OFFICE.

CLAYTON A. GOODSELL, OF HARVARD, ILLINOIS.

SASH-LOCK.

SPECIFICATION forming part of Letters Patent No. 718,118, dated January 13, 1903.

Application filed June 13, 1902. Serial No. 111,590. (No model.)

To all whom it may concern:

Be it known that I, CLAYTON A. GOODSELL, a citizen of the United States of America, residing at Harvard, in the county of McHenry 5 and State of Illinois, have invented certain new and useful Improvements in Sash-Locks, of which the following is a specification.

My invention relates to certain improvements in sash-locks adapted for application 10 to the side rails of a window-sash and intended to provide means for fastening the two sash together and also preferably for fastening one of the sash to the window-frame.

To such ends the invention consists in certain 15 novel features below described and claimed.

In the drawings, Figure 1 is an elevation of the part of a window-frame and window-sash to which the fastener is applied. Fig. 2 is a 20 horizontal section in the line 2 2 of Fig. 1. Fig. 3 is a perspective of certain parts of the device, showing the casing in dotted lines. Fig. 4 is a horizontal section in the line 4 4 of Fig. 1. Fig. 5 is a section in the line 5 5 25 of Fig. 4 looking in the direction of the arrow, and Fig. 6 is a section in the line 6 6 of Fig. 4 looking in the direction of the arrow.

Referring to the drawings, A is the window-frame; B B', the upper and lower sash, 30 respectively. The upper sash is provided with a series of holes or bolt-sockets b, and upon one side of the top of the lower sash is secured a frame or casing C, designed to support and preferably inclose and conceal the 35 working parts of the fastener. In the window-frame are a series of holes adapted to serve as bolt-sockets a, and a bolt D is guided longitudinally of the casing in openings c' and engages the sockets a to secure the 40 lower sash to the frame. On the bolt D is a collar d, Fig. 2, adapted to engage a lug a' on the casing to hold the bolt either in the sockets or entirely out of the same. A spring H between the collar and the opposite side of 45 the casing tends to thrust the bolt into the sockets. Fig. 5 shows the preferred shape of the lug a', and the same is preferably limited in lateral extent, so as to pass through a notch d' in the collar to permit the bolt to be 50 drawn back. In the front and rear walls of the casing are slots c³ c², through which extends a transverse bolt E, which carries with-

in the casing a slide F of the form shown in Fig. 3, provided with a trough-shaped channel f, through which the bolt E extends. The 55 trough-shaped channel permits a lug e on the bolt to pass through when the bolt is turned to the proper position. An indicator e² on the handle portion of the bolt indicates from the outside when the bolt is in this position. 60 A similar indicator on the handle of the bolt D indicates the position of the notch in the collar d. A loose collar e' on the bolt E furnishes a bearing for a spring G, which also bears on the lug e to crowd the bolt E into the 65 sockets b. On the slide F is an arm f⁴, extending through the casing and guided therein and provided outside of said casing with a portion f⁵, extending toward the upper sash and terminating in a roller f⁶, adapted to run upon the 70 inner edge of said sash, as seen in Fig. 2. The slide F rides against a guide c⁵, raised from the bottom plate of the casing, which keeps the slide from tilting or wabbling. A plate f⁷, supported upon a lug f⁸, extending from the 75 slide F, furnishes a bearing for a coiled spring f⁹, the other end of which bears upon the casing and tends to crowd the slide toward the right in Fig. 4, so as to cause the roller f⁶ to bear upon the upper sash. By this means 80 the bolt E is kept in the vertical plane of the opening b regardless of any relative lateral movement of the sash one with respect to the other. The arm f⁴ is provided at its inner 85 end with a loop or hook f¹⁰, having one end in engagement with a hole f¹¹ in the slide F. It will be seen that by pulling the roller away from the edge of the sash at a time when the bolt E is not in one of the sockets b and then holding the bolt E in this position the hook 90 can be disengaged from the hole f¹¹ by again pushing the roller toward the sash and the roller can be swung up out of the way of the sash when it is desired to place the lower sash above the upper one for cleaning or other 95 purposes. The slide F provides means for holding the bolt E in position to engage the upper sash or withdrawn therefrom, so as to permit of the free movement of said upper sash. Said slide F has a projecting lug f¹² 100 running through the casing and bearing upon the frame. This lug supplements the roller f⁶ and is intended for the same purpose. Upon the top of the slide F and carried there-

by is a telescoping plate composed of two portions I' and I^2 , which slide one upon the other. The plate I' has a hook i at one end which is adapted to be engaged by the lug e upon the bolt E . The reason for the use of the telescoping slide is that while the bolt moves a considerable distance the rear end of the slide is able to move up a short distance. For this reason I use the telescoping plate, so that the portion attached to the bolt may move a considerable distance while the other portion will only move a short distance. This construction is clearly shown in the drawings and its operation will be understood. The plate I^2 has an upturned end i' , which when the bolt E is in engagement with the upper sash is in the normal path of the collar d upon the bolt D . It will be obvious, therefore, that when the bolt E is closed the bolt D must also remain closed. A shoulder i^2 upon the plate I^2 also engages a lug J upon the casing. This locks the bolt E in a closed position. A second lug J' , together with the lug J , furnishes a support for one end of the telescoping plate, the other end of which rests upon the slide F . A rib f^{12} upon said slide forms a guide for the plate I' I^2 while it is upon the slide. It will be seen, therefore, that when this bolt is closed the projecting portion i^2 must be removed from engagement with the lug J . The bolt E must then be drawn back, also withdrawing the upturned portion of the telescoping plate from the path of the collar d before the second bolt D can be withdrawn. This is accomplished by slightly pulling the bolt D . It will be seen that this will bring the collar d into engagement with the upturned portion i' and force it a slight distance to the left in Fig. 4, therefore releasing its engagement with the lug J . The lug J' allows the plate but very slight lateral movement, simply enough to permit the shoulder i^2 to be released from the lug J . It will thus be understood that the bolt D cannot be released until the bolt E is first withdrawn because of the upturned end i' and lug J' .

A plate M , secured upon the arm f^4 and connected to the front of the casing C by a screw m , furnishes means for producing lateral movement to said arm for the purpose of adapting the lock to different thicknesses of sash. By turning said screw the roller is caused to move toward or away from the casing C , and therefore into proper engagement with the upper sash.

By the devices heretofore described either or both of the bolts may be secured in its rear-most position. It will be observed that this forms a very simple and convenient lock and one which it is absolutely impossible to open from outside of the window—that is to say, with a lock of this sort burglary from without would be practically impossible, as a hole large enough to admit two hands would have to be made in the window before the lock could be operated at all.

I realize that considerable changes can be made in the details of this construction, and I do not, therefore, desire to limit myself to the specific construction herein shown.

I claim as new and desire to secure by Letters Patent—

1. In a sash-lock, a suitably-guided bolt adapted to engage sockets in one of the window-sash and a suitably-supported roller adapted to guide the bolt in the plane of the sockets and capable of being swung into a position out of the plane of sash, substantially as described. 75

2. In a sash-lock, a bolt adapted to engage one of the sash of the window to lock both sash together, a slide mounted upon said bolt and an arm connected to said slide and bearing a roller adapted to run upon said sash to 85 guide the bolt, the arm being so pivoted to the slide as to permit the roller to be swung out of the plane of the sash, substantially as described.

3. In a sash-lock, the combination with a bolt adapted to engage sockets in the upper sash, of a laterally-movable slide mounted upon said bolt, a roller running upon the upper sash and adapted to guide the bolt in the plane of the sockets, an arm carrying said 95 roller and pivotally connected to the guide and suitable means for holding it either in position upon said upper sash, or out of the plane thereof, substantially as described.

4. The combination with a bolt and slide 100 mounted thereupon, of a roller-carrying arm having a hook, f^9 , adapted to be seated in suitable holes in the slide, substantially as described.

5. In a sash-lock, the combination with a 105 bolt, extending transversely of the sash, a second bolt extending longitudinally thereof, and a slide-plate having a portion adapted, when in one position, to lock the second bolt against withdrawal, and adapted to be engaged by the first-named bolt, so as to move therewith, whereby when said first-named bolt is in a locked position, the second will also be locked against withdrawal, substantially as described. 110

6. The combination with a suitable casing, of the bolts, D , E , a suitably-guided slide having suitable means for engagement with the bolt, E , and a stop for the bolt, D , adapted by the movement of the bolt, E , to be brought 120 into or out of engagement with the bolt, D , substantially as described.

7. The combination with a casing, of the bolts, D , E , the slide, F , and the spring-pressed plate, I' , I^2 , having an upturned end, i' , said 125 upturned end being adapted to be brought into the path of the bolt, D , by the action of the bolt, E , substantially as described.

8. The combination with a casing, of the bolt, D , having a collar, d , and the telescoping slide, I' , I^2 , having the upturned end, i' , adapted to be brought into or out of engagement with the collar, d , substantially as described. 130

9. In a sash-lock, the combination with a suitable casing, a slide, F, having a trough-shaped groove, a bolt guided in said slide and having a lug moving in the trough and adapted to engage the slide on either end thereof and an indicator on said bolt without the casing adapted to show the position of said lug, substantially as described. 5
10. In a sash-lock, the combination with a suitable casing, of the bolt, D, formed with the collar, d, a suitably-guided slide, F, a bolt, E, sliding in said guide and having the lug, e, the telescoping plate, I', I², having a hook, i, an upturned end, i', a plate, f⁷, engaging said slide and plate and the spring, f⁸, substantially as described. 15
11. In a sash-lock, the combination with a casing and the bolt, E, of the spring-pressed slide, F, the roller, f⁶, connected therewith and adapted to position the bolt with regard to the upper sash, and the lug, f¹¹, sliding in the casing and adapted to guide said slide in its lateral motion, substantially as described. 20
12. In a sash-lock, the combination with a casing and the bolt, E, of the spring-pressed slide, F, the roller, f⁶, connected therewith and adapted to position the bolt with regard to the upper sash but capable of being swung out of the plane thereof, substantially as described. 25
13. The combination with a pair of sash and a series of sockets, b, in one of said sash, of a spring-pressed slide, F, mounted on the other of said sash, a bolt, E, in said slide, a lug f¹¹, connected to said slide and adapted to hold said bolt, E, in a vertical line with said sockets, b, substantially as described. 30

In witness whereof I have hereunto set my hand, at Harvard, in the county of McHenry and State of Illinois, this 9th day of June, 40

A. D. 1902.
